[57] CLAIM

The ornamental design for a decorative trim for a valance, as shown and described.

DESCRIPTION

FIG. 1 is a perspective view of a decorative trim for a valance, showing my new design;

FIG. 2 is a front elevational view thereof;

FIG. 3 is an end view with the opposite end being a mirror image thereof;

FIG. 4 is a perspective view of the second embodiment of the design shown in FIG. 1;

FIG. 5 is a front elevational view thereof; and,

FIG. 6 is an end view with the opposite side being a mirror image thereof.

The undisclosed rear elevational view is planar and unornamented.

FIG. 3

FIG. 2

FIG. 4

FIG. 5

FIG. 6
